UNITED STATES PATENT OFFICE

165,076

COMBINED JARS AND TRAY UNIT

Joseph A. Hill, Glen Ellyn, Ill.

Application May 19, 1951, Serial No. 15,249

Term of patent 7 years

(Cl. D44—9)

To all whom it may concern:

Be it known that I, Joseph A. Hill, a citizen of the United States, residing at Glen Ellyn, county of Du Page and State of Illinois, have invented a new, original, and ornamental Design for a Combined Jars and Tray Unit, of which the following is a specification, reference being had to the accompanying drawing, forming a part thereof, in which:

Fig. 1 is a perspective view of a combined jars and tray unit, showing my new design; Fig. 2 a top plan view; Fig. 3 an end view, each end being identical; Fig. 4 a front view in elevation, the rear view being identical; and Fig. 5 a transverse sectional view, the section being taken as indicated at line 5—5 of Fig. 2.

I claim:

The ornamental design for a combined jars and tray unit, as shown and described.

JOSEPH A. HILL.
